DESIGN FOR A FLOWER MOUNTED LAPEL WATCH

David Ornstein, New York, N. Y.

Application February 26, 1940, Serial No. 90,513

Term of patent 3½ years

To all whom it may concern:

Be it known that I, David Ornstein, a citizen of the United States, residing at 129 West 22nd Street, New York, in the county of New York and State of New York, have invented a new, original, and ornamental Design for a Flower Mounted Lapel Watch, of which the following is a specification, reference being had to the accompanying drawing, forming a part thereof.

In the drawing:

Fig. 1 is a front elevational view of a flower mounted lapel watch showing my new design, the rear of the same being plain.

Fig. 2 is a side elevational view of the same.

The design consists in placing a small watch

dial into an ornamental ring. A few, large, almond shaped petals radiate in an irregular manner from said ring, which forms the center of the flower imitated by my watch case. A thin stem depends in an irregular manner from said watch flower design, and two upwardly inclined leaves, similar to said petals are arranged on the stem. The almond shaped leaves and petals have second marginal lines following their outer contours at a small distance therefrom.

I claim:

The ornamental design for a flower mounted lapel watch, as shown and described.

DAVID ORNSTEIN.
